UNITED STATES PATENT OFFICE.

JONATHAN K. JAEGER, OF FENWOOD, SASKATCHEWAN, CANADA.

ENGINE.

1,271,471.

Specification of Letters Patent.

Patented July 2, 1918.

Application filed September 15, 1915. Serial No. 50,847.

To all whom it may concern:

Be it known that I, JONATHAN K. JAEGER, a subject of the King of Great Britain, residing at Fenwood, in the Province of Saskatchewan, Dominion of Canada, have invented new and useful Improvements in Engines, of which the following is a specification.

This invention relates to internal combustion engines and more particularly to the control mechanism therefor and has for its primary object the provision of a structure wherein the exhaust valves are opened at predetermined intervals through the action 15 of the piston rod, as the latter approaches its limit of travel in one direction.

A further object of the invention is the provision of rotary means coöperating with the piston rod whereby the exhaust valve 20 rods are given a reciprocatory motion at predetermined intervals.

A still further object of the invention is the provision of link mechanism under the control of the piston rod whereby the exhaust valves are returned to closed position 25 subsequent to being opened by the rotary mechanism under the control of the piston rod.

The invention consists in the features of 30 construction, combination, and arrangement of parts, hereinafter fully described and claimed, reference being had to the accompanying drawings, in which:—

Figure 1 is a top plan view of my improved form of combustion engine.

Fig. 2 is a longitudinal section therethrough showing the pistons in elevation.

Fig. 3 is a side elevation.

Fig. 4 is an end elevation.

Figs. 5, 6, 7, and 8 are sectional views 40 through the valve controlled mechanism.

Fig. 9 is a view through a governor working in conjunction with my invention.

Fig. 10 is a detail view illustrating the 45 application of the governor to the piston rod.

Fig. 11 is a fragmentary sectional view of the pressure reducing valve.

Referring to the drawings, the numeral 1 50 designates the fluid pressure tank with which the engine cylinder 2 has communication. The cylinder is subdivided by a partition 3 into a pair of chambers 4 and 5.

Reciprocating within the chamber 4 is a piston 6 while reciprocating within the 55 chamber 5 is a piston 7 both fixedly secured to a piston rod 8. Communication between

the chambers of the cylinders and the interior of the tank 1 is had by means of the exhaust valves 9 and 10, the former communicating with the combustion chamber *a* 60 and the latter communicating with the combustion chamber *b*. Also communicating with the chambers are the intake valves 11 and 12 that communicate with any well known form of carburetor.

The inner end portion of the chamber 4 has communication with the interior of the tank by way of the pipe 13 provided with a valve 15 of a construction to allow rapid flow from the chamber 4 to the interior of 70 the tank 1 but only allow a slow return.

From the arrangement above described, it will be understood that when the burned gas is exhausting from one of the combustion chambers, it passes by the respective exhaust valve into the tank 1 while sufficient air and burned gas combined passes through the pipe 13 into the chamber 4 behind the piston to assist in the return movement of both pistons and the piston rod. When an explosion occurs in the chamber *a* (see Fig. 2) the piston 7, and with it the piston 6, will be forced toward the right and as a result, an explosive charge will be drawn into the chamber *b*. The valve in the pipe 13 allows 80 the air and gas to flow rapidly from the chamber 4 to the tank 1 and to return slowly from the tank to the chamber 4 as the piston returns. As the piston makes its return movement, the burned gas is forced through 85 the respective exhaust valve into the tank 1. The same operation just above described takes place with respect to the chamber *b*, the explosions occurring alternately in the chambers *a* and *b*.

The piston rod 8 extends beyond one end wall of the cylinder and has its under surface provided with a rack bar 16 while connected to one end of the rack bar 16 is a chain 17 engaging at one extremity the drum 18 secured upon a horizontally disposed shaft 19.

Coöperating with the shaft 19 is a coil spring 20, the resiliency of which opposes outward movement of the piston rod. Arranged to coöperate with the rack bar 16 is a mutilated gear 21, the teeth of which covers one-half the periphery of the gear. This mutilated gear is rigidly secured to a horizontal shaft 22 having its extremities 105 journaled in bearings 23. Upstanding from a base 24, the shaft 22 is formed with three

crank arms 25, 26, and 27, and bearing against said shaft are one or more horizontal leaf springs 28 (see Figs. 1, 3 and 4) by means of which the crank arms 25 and 26 are normally held at an incline with relation to the base 24.

Coöperating with the crank arms 25 and 26 are vertical portions 29 and 30 of slide rods 31 and 32 (see Fig. 5). These slide rods are mounted to reciprocate in guides 32' and have their adjacent extremities formed with eyes 33 and 34 encircling the exhaust rods 35 and 36 respectively. These exhaust rods are connected to the movable portion of the heretofore mentioned exhaust valve rods 9 and 10.

Encircling each of the exhaust valve rods is a pair of springs 37 and 38, the latter being stronger than the former. The spring 37 abuts an eye of a slide rod while the spring 38 abuts one of the supports for the slide rod, and arranged between the springs and rigidly secured to an exhaust valve rod is a washer 39, arranged to coöperate with a keeper plate 40. Attention is called to the fact that while I have only described the structure for operating one of the exhaust valves, I wish it to be understood that the construction for the other exhaust valve is identical.

The keeper plate 40 of the exhaust valve 9 and the keeper plate 41 of the exhaust valve 10 are connected by links 42 with a rod 43 that is pivotally connected with an arm 44 formed upon a shaft 45 that is further provided with an arm 46 disposed in the path of movement of a lug 47 secured upon the piston rod. The lug 47 and the lug 48, each of which is provided with a knuckle or hinge joint, are adapted to coöperate with the laterally extending pins 49 and 50 on the mutilated gear 21.

From the foregoing description, it will be seen that when a piston rod moves outwardly, the rack bar engages the teeth of the mutilated gear 21 so as to give the shaft 22 a partial rotation for actuating one of the slide rods by one of the crank arms 25 or 26, for opening either one of the exhaust valves 9 or 10. Simultaneously with this action, the spring 20 is put under tension by the piston exerting a pull upon the chain 17. As the crank arms 25 and 26 are disposed 180° apart, the spring of one of the exhaust valve rods will be put under tension upon partial rotation of the shaft 22 through the action of the rack bar and gear. Upon compression of the springs, the washer 39 is forced past one of the keeper plates where it will be held against further movement until released by the lug 47 striking the arm 46 thus giving the keeper plate a partial rotation for releasing the washer which allows the springs to regulate for opening the exhaust valve.

For preventing excessive pressure within the tank 1, I secure to the piston rod a finger 51 adapted to engage the teeth 52 of a pivoted arm 53 when the pressure in the tank reaches a predetermined maximum. 70 Coöperating with the arm 53 is a rod 54 the lower extremity of which is secured to a piston 55 against the under surface of which the air pressure of the tank 1 acts. The piston 55 is inclosed by a cylinder 56 mounted on the base 24 under the arm 53 and as shown is provided with laterally extending lugs 57 through which pass screws 58 that engage a cross bar 59 bearing upon a coil spring 60 that encircles the piston rod and bears upon the piston 55. When the pressure in the tank 1 reaches a predetermined maximum, the piston 55 will be forced upwardly against the tension of the spring for throwing the teeth 52 of the arm 53 in the path of movement of the finger 51. When this takes place, the pistons within the cylinder are held against further movement until the pressure within the tank is reduced. 90

The apparatus is intended as a compressing pump designed to build up pressure in the tank 1 from which it may be used for any power purposes desired. The chamber 4 is intended to receive sufficient pressure 95 to partially balance the pressure in either of the chambers *a* and *b* to allow the spring 20 to return the pistons 6 and 7 to the position shown in Fig. 2. The valve 15 is a pressure reducing valve and allows the pressure to move slowly from the tank 1 to the chamber 4 and vice versa. 100

Having described the invention, what is claimed is:

1. In combination, a cylinder having a fluid tight head between its ends and combustion chambers at opposite sides of said head, a piston working in each chamber, a piston rod connected thereto, an exhaust valve for each chamber, means for allowing gas to enter said chambers alternately, valve rods under the control of said piston rod for alternately opening said exhaust valves at predetermined intervals, springs encircling each of said valve rods and acting in opposition to each other, means under the control of said piston rod for compressing one spring through the compression of the other spring, and means for holding said springs under compression for predetermined intervals. 115

2. In combination, a cylinder having a fluid tight head between its ends and combustion chambers at opposite sides of said head, a piston working in each chamber, a piston rod connected thereto, an exhaust valve for each chamber, means for allowing gas to enter said chambers alternately, valve rods under the control of said piston rod for alternately opening said exhaust valves 125 130

at predetermined intervals, springs encircling each of said valve rods and acting in opposition to each other, means under the control of said piston rod for compressing 5 one spring through the compression of the other spring, means for holding said springs under compression for predetermined intervals, a washer arranged on each valve rod and interposed between said springs, a second rod for contracting said springs, and means under the control of said piston rod coöperating with said washer for holding 10 said spring under pressure.

3. In combination, a cylinder having a 15 fluid tight head between its ends and combustion chambers at opposite sides of said head, a piston working in each chamber, a piston rod connected thereto, an exhaust valve for each chamber, means for allowing 20 gas to enter said chambers alternately, valve rods under the control of said piston rod for alternately opening said exhaust valves at predetermined intervals, a rack bar secured to the under surface of said 25 piston rod, a mutilated gear coöperating with said rack bar, a crank shaft upon which said mutilated gear is mounted, and means coöperating with said crank shaft for operating said exhaust valve.

30 4. In combination, a cylinder having a fluid tight head between its ends and combustion chambers at opposite sides of said head, a piston working in each chamber, a piston rod connected thereto, an exhaust 35 valve for each chamber, means for allowing gas to enter said chambers alternately, valve rods under the control of said piston rod for

alternately opening said exhaust valves at predetermined intervals, a rack bar secured to the under surface of said piston rod, a 40 mutilated gear coöperating with said rack bar, a crank shaft upon which said mutilated gear is mounted, means coöperating with said crank shaft for operating said exhaust valve, and resilient means for holding 45 the crank portion of said shaft normally in an inclined position.

5. In combination, a cylinder having a fluid tight head between its ends and combustion chambers at opposite sides of said head, a piston working in each chamber, a piston rod connected thereto, an exhaust valve for each chamber, means for allowing gas to enter said chambers alternately, valve rods under the control of said piston rod 50 for alternately opening said exhaust valves at predetermined intervals, a rack bar secured to the under surface of said piston rod, a mutilated gear coöperating with said rack bar, a crank shaft upon which said mutilated gear is mounted, slide rods coöperating with the crank portions of said shaft and other rods connected to said exhaust valve and having resilient connection with said slide rods, and resilient means for holding the crank portion of said shaft normally in an inclined position.

In testimony whereof I affix my signature in presence of two witnesses.

JONATHAN K. JAEGER.
